UNITED STATES PATENT OFFICE.

OTTO L. ENGSTROM, OF SOUTH BEND, INDIANA.

CONCRETE-WALL FORM.

Application filed May 18, 1926. Serial No. 109,921.

This invention relates to a concrete wall form construction, and has for its object to provide, in a manner as hereinafter set forth, a series of units of simple construction which may be expeditiously assembled and secured in position to provide a wall forming cavity for the reception of the concrete.

This invention has to do particularly with sheet metal forms that may be used repeatedly whereby the cost for operation is comparatively small. Although the initial outlay for the metallic forms may be greater than that required for wooden forms, nevertheless, the simplicity of a form, in accordance with this invention, as well as its durability provides for a material saving in expenses over the employment of wooden frames or forms as a material portion of these latter 20 are discarded after the erection of the building.

Further objects of the invention are to provide, in a manner as hereinafter set forth, an all metal concrete wall form which is comparatively simple in construction and arrangement, strong, durable, thoroughly efficient in its use, conveniently erected, comparatively inexpensive to set up and providing for a material saving in expense with 30 respect to the known forms now generally employed.

With the foregoing and other objects in view, the invention consists of the novel construction, combination and arrangement 35 of parts, as hereinafter more specifically described and illustrated in the accompanying drawings, wherein is shown an embodiment of the invention, but it is to be understood that changes, variations and modifications 40 can be resorted to which fall within the scope of the claims hereunto appended.

Figure 1 is a fragmentary view, in sectional plan, of a wall form in accordance with this invention.

Figure 2 is a fragmentary view, of an all metal wall form in accordance with this invention looking towards one of the outer sides thereof.

Figure 3 is a section on line 3—3, Figure 1.

Figure 4 is a front elevation of an outside corner post.

Figure 5 is a fragmentary view, in vertical section of the form when set up.

Figure 6 is a perspective view of the form of spanner employed.

Figure 7 is a fragmentary view, in perspective of the form of wall panel employed.

Figure 8 is a fragmentary view in perspective, of the corrugated backing plate for 60 the wall panel.

Figure 9 is a vertical sectional view of a corner post.

Figure 10 is a fragmentary view, in elevation, of one of the side posts. 65

Figure 11 is a fragmentary view illustrating a different position of the combined anchoring and bracing means.

An all metal concrete form, in accordance 70 with this invention, includes outer wall units termed outer wall panels and inner wall units, termed inner wall panels. The outer wall panels are arranged in sets and the sets correspond in number to the number of outer walls. The inner wall panels are ar-

75 ranged in sets, and the sets correspond in number to the number of inner walls. The outer wall panels are constructed similar to and of the same size as the inner wall panels, with this exception, that the corner panels 80 of the set or sets of the outer wall panels are of greater width than the other panels of the set or sets of the wall panels. The panels for the outer wall of the cavity are indicated generally by the reference character 1

85 and the panels for the inner wall of the cavity are indicated generally by the reference character 2. The wall cavity is indicated at 3. The corner panels of the set or sets of panels for the outer wall or walls of 90 the cavity are indicated at 4. The corner panels of the set or sets of panels for the inner wall or walls are indicated at 5. By reference to Figure 1 it will be observed that the panels 4 are of greater width than the panels 1, 2 and 5 and which arrangement is necessary when forming the corners at the

95 point of joinder of one wall with the other wall of the concrete structure. The panels 4 must project beyond the panels 5 to provide for the joining of one wall with another wall in alignment with respect to an inner and an outer corner disposed in a diagonal plane. See Fig. 1.

The panels 1 of the front wall, as well as 105 the panels 2 of the rear wall, of the form, each consists of a vertically disposed metallic plate 6 of the desired height, width and thickness. The plate 6 is formed with a smooth inner and outer face. Extending 110 outwardly from the top of the plate 6 as well as from the bottom thereof are right

angularly disposed flanges 8 and 9 respectively. The flange 8 consists of a horizontally disposed leg 10 formed with oppositely disposed inclined ends 11, 12. The leg 10 at 5 its outer end merges into a vertically disposed depending leg 13 which corresponds in contour to the shape of the leg 10. The flange 9 includes a horizontally disposed leg 14 which corresponds in contour to the 10 contour of the leg 10 and said flange further includes a vertically disposed upstanding leg 15 at the outer end of the leg 14. The flanges 8 and 9 are angle shaped in cross section and are oppositely disposed 15 with respect to each other. Extending outwardly from each side of the plate 6 is a pair of flanges 16 and 17 which are oppositely disposed with respect to each other, overlap the outer face of the plate, and each 20 of which is formed with a rounded inner portion 18 and an outer portion 19 disposed at an angle with respect to the portion 18 and which opposes and is arranged in parallelism with respect to the outer face of the 25 plate 6, but spaced therefrom.

The flanges 8, 9, 16 and 17 provide means for coupling with the panel a retaining or backing plate therefor and the latter consists of a corrugated metallic plate 19. The 30 corrugations of the plate 19 extend lengthwise thereof, as indicated at 20 and said plate 19 when positioned between the flanges of the panel extend from the flange 8 to the flange 9 and from the flange 16 to the flange 35 17. The plate 19 acts as a means for reinforcing the plate 6 of the panel to prevent the bending or bulging of the latter by the weight or rather body of concrete 21 when the latter is supplied to the wall-forming 40 cavity 3. The flanges 16 and 17 confine the plate 19 in its corrugated state or in other words prevent the expanding of the plate 19 when mounted in position with respect to its associated panel.

45 Interposed between the panels forming the outer wall of the form, or the panels forming the inner wall of the form, is a vertically disposed side post unit and each of these latter units are referred to generally 50 by the reference character 22, see Figures 1, 5 and 10. The several side posts employed are constructed throughout of metal and the side posts used in connection with the outer walls of the form are oppositely 55 disposed with respect to the side posts employed with the inner wall of the form. As the several side posts are of the same construction, but one will be described as the description of one will apply to the other. 60 The position of a side post with respect to the outer wall of the form is clearly shown in Figure 2 and it is of a height to extend from the bottom to the top of a wall panel. Each side post consists of a channel bar 23 65 opening outwardly and formed with a pair

of oppositely disposed laterally extending flanges 24. Secured to the channel bar 23 is a rectangular metallic strip 25 of the same length as the length of the bar. The width of the strip 25 corresponds to the combined 70 width of the body portion and flanges of the bar. The strip 25 opposes the flanges 24 and provides in connection with these latter a pair of oppositely disposed pockets 26 for receiving the opposed sides of a pair of wall 75 panels, see Figure 1. The strip 25 when a wall of the form is set up is arranged within the wall cavity 3. The flanges 24 are positioned exteriorly of the wall cavity 3. The flanges 24 also provide abutments for 80 bracing units to be presently referred to. Each side post is formed with spaced pairs of vertically extending slots. The slots of each pair are indicated at 27, 28. The slot 27 is of greater length than the slot 28 and 85 is arranged above but in proximity to the slot 28. The pairs of slots of a side post in an outer wall of the form oppose the pairs of slots in a side post in the inner wall of the form. The function of the pairs of slots 90 will be presently referred to. The pairs of slots are formed at the vertical median of the strips 25 and at the vertical median of the closed inner side of the bar 23.

The form further includes outside corner 95 post units and inside corner post units. The outside corner posts are indicated generally by the reference character 29 and the inside corner posts are indicated generally by the reference character 30. Each outside 100 corner post consists of an outer angle-shaped bar 31 and an inner angle-shape bar 32. Each bar is in the form of a corner iron and consists of two legs extending at right angles with respect to each other. The bar 105 31 is of the same length as the bar 32 and each corner post is of the same height as a wall panel or side post. The bar 31 is fixedly secured against the outer face of the bar 32 by the hold fast devices 33. 110

Each leg of the bar 31 consists, in cross section, of a pair of end portions disposed in spaced parallel planes and an inclined intermediate portion projecting away from the bar 32, and the latter in connection with 115 the outer end and intermediate portions of the legs of the bar 31 provide a pair of oppositely disposed pockets 34, 35 throughout the length of the posts to receive the outer sides of the corner panels of the outer 120 sets. See Figure 1. The corner post at the point of joinder of the legs of the bar 31 and legs of the bar 32 is formed with spaced pairs of vertically disposed slots. The slots of each pair are indicated at 36, 37 see Figure 125 9 and the slot 36 is of greater length than the slot 37 and is arranged above the latter, as well as in close proximity therewith. The function of the slots will be presently referred to. 130

Each inside corner post consists of an inner bar 38 and an outer bar 39. Each inside corner post is constructed in the same manner as each outside corner post. The 5 pairs of slots formed in the inside corner post oppose and are arranged in alinement with the pairs of slots formed in the outside corner post. The pockets formed in the inside corner posts are indicated at 40, 41, to 10 receive the outer sides of the corner panels of the inner sets, see Figure 1.

The form further includes sets of standards of metallic material and one set associates with the outer wall of the form and 15 the other set with the inner wall of the form. Each of the standards of the set has associated therewith an anchoring element therefor which is also constructed of metallic material. Each standard of each of the sets 20 consists of a vertically disposed narrow metallic bar 42 of the same height as the height of a wall panel and which has secured to one side face thereof a plurality of inwardly extending spaced supports 43 and each of the 25 latter is in the form of a bracket consisting of a horizontally disposed arm 44 and a vertically disposed arm 43. The outer end of the arm 44 is fixedly secured to the bar 42 by the hold fast devices 45. The inner 30 end of the arm 44 terminates in the vertically disposed arm 43 and which is spaced a substantial distance from the bar 42 and when the standard is set up in active position the arm 45, as well as the inner end 35 of the arm 44 abuts against the corrugated plate 19, see Figure 3. The bar 42 is of angle shape in cross section to form a pair of right angularly disposed legs 47, 48, see Figure 1 and to the leg 47 is secured the 40 outer end of the arm 44 of the bracket 43. In cross section the leg 48 of the bar 42 projects at right angles with respect to the inner side of the leg 47 and also at right angles with respect to the arm 44 of the 45 bracket 43. The supports or brackets 43 provide means for supporting sectional brace members, to be presently referred to, and the legs 48 of the bars 42 provide confining means for said brace members and 50 the flanges of the side post form abutments for the brace members. The supports or brackets 43 carried by the standards of the set aline with each other. Each bar 42 at its top provided with a pair of openings 55 52, see Figure 2.

The bracing means or rather anchoring means for each standard consists of an anchoring element 49 which is secured in and projects above the ground and has connected to its projecting portion by hold fast devices 50 an upstanding inwardly inclined brace rod 51 which at its upper end is connected by the hold fast devices 52' to the upper end of the leg 47 of the bar 42, see 60 Figure 3 and the arrangement of the brace 65

or anchoring means is illustrated in dotted lines. Further the arrangement of the brace or anchoring means for each of the standards is also shown in dotted lines in Figure 1. The hold fast devices 52' extend through 70 the openings 52. The bracing or anchoring means can be positioned as shown in Figure 11.

The form further includes sets of superposed spanners formed of metallic material 75 and each set extends from an outer to an inner wall of the form and further extends across the cavity 3. The spanners of the set are detachably mounted in the walls of the form so that when the walls are knocked 80 down, the spanners will be anchored within the concrete body 21. Each spanner is referred to generally by the reference character 53, see Figure 6 and is formed of an inverted L-shaped body portion 54 provided 85 at each end with a lug 55 of materially less width than the width of the top of the body portion 54 of the spanner. The lugs of each spanner are seated in opposing slots 28 in the side posts see Figure 5 and also in 90 opposing slots 37 in the corner posts, see Figure 1.

The form further includes wire ties which associate with the sectional brace members or elements to be presently referred to. The wire ties are referred to generally by the reference character 56, see 95 Figure 5, and each tie extends through a pair of alining slots 27 formed in the side posts and also through a pair of alining 100 slots 36 formed in the corner posts.

The form further includes a set of sectional brace members or elements for the outer wall of the form and a set of sectional brace members or elements for the inner wall 105 of the form. The brace members or elements of each set are arranged in superposed spaced relation and the brace members or elements for the outer wall of the form are connected to the brace members or elements 110 for the inner wall of the form through the medium of the wire ties. The brace members or elements for the outer wall of the form are mounted upon the supports or brackets 43 carried by the outer set of standards and the brace members or elements for the inner wall of the form are mounted upon the supports or brackets 43 carried by the inner set of standards. See Figure 1 in this connection. Each outer brace member or element corresponds in contour to the contour of the form and each inner brace member or element corresponds in contour to the contour of the form. Each brace member or element comprises tubular sections 57 and 125 tubular sections 58 corresponding in contour to the shape of an elbow coupling. The sections 58 are arranged at the corners of the form. The sections 57 are arranged at the side and ends of the form. The sections 130

are connected together by cylindrical members 59 which are mounted in the opposed ends of the pair of sections and are secured therewith by holdfast devices 60. The tubular sections of the outer set of brace members or elements, as well as the elbow-shaped section 58 are adapted to extend through the outer ends 61 of the wire ties 56, see Figure 5, and the sections of the inner set of brace members are adapted to extend through the inner end 62 of the wire ties 56. The wire ties employed at the corner of the form are of greater length than the ties arranged at the sides and ends of the forms but the ties are similar in construction, the only difference being in the length as stated. The wire ties are of the twisted type and are twisted to provide for the abutting of the brace members against the flanges of the side posts.

23 When the form is set up the panels 4 extend into the pockets 34, 35 and the panels 5 extend into the pockets 40, 41, see Figure 1. The corner pieces, when the panels 4 and 5 abut thereagainst provide for setting up 25 the inner and other corners of the concrete wall and said corner pieces form closures between the corner panels. The wall forming panels also extend into the pockets 26 formed by the side posts, see Figure 1. The 30 brace members or elements abut against the corrugated plates 19.

The units of the form can be expeditiously assembled and retained in set position to provide for the wall cavity 3 to receive the 35 concrete body 21 and after the latter has been set, the wire ties are severed so that the brace members or elements will be free thereof. The wire ties are embedded in the concrete body when the form is knocked 40 down. The various units of the form can be of any size desired. To insure from rust and concrete sticking to the units these latter may be mopped or brushed with some cheap oil. The brace members or elements 45 securely maintain the panels, side posts and corner posts in set position or rather in connection with the wire ties and spanners the shape of the form is maintained and further held in such position by the standards 50 and anchoring means for these latter.

It is thought the many advantages of an all metal concrete form, in accordance with this invention, can be readily understood, and although the preferred embodiment of 55 the invention is as illustrated and described, yet it is to be understood that changes in the details of construction can be had which fall within the scope of the invention as claimed.

60 What I claim is:

1. In a concrete wall form construction outer sets of metallic wall forming members, said sets disposed at right angles with respect to each other, inner sets of metallic wall forming panels, said inner sets dis-

posed at right angles with respect to each other, metallic corner posts positioned between said outer sets, metallic corner posts positioned between said inner sets, side posts interposed in each of said sets and each provided with oppositely disposed means for receiving a pair of panels, bracing elements arranged against the outer side of said outer set, bracing elements arranged between the outer side of said inner set, tie members for connecting said corner posts and brace elements together, tie members for connecting said brace elements and side posts together, spanner elements arranged between the said outer and inner posts and supported thereby, and braced standards provided with supports for said bracing elements, said supports bearing against said panels.

2. In a concrete wall form construction outer sets of metallic wall forming members, said sets disposed at right angles with respect to each other, inner sets of metallic wall forming panels, said inner sets disposed at right angles with respect to each other, metallic corner posts positioned between said outer sets, metallic corner posts positioned between said inner sets, side posts interposed in each of said sets and each provided with oppositely disposed means for receiving a pair of panels, bracing elements arranged against the outer side of said outer set, bracing elements arranged between the outer side of said inner set, tie members for connecting said corner posts and brace elements together, tie members for connecting said brace elements and side posts together, spanner elements arranged between the said outer and inner posts and supported thereby, braced standards provided with supports for said bracing elements, said supports bearing against said panels and each of said wall forming panels having a backing means therefor arranged on the outer side thereof.

3. In a concrete wall form construction, spaced outer and inner walls each consisting of a set of sidewise opposed removable wall forming panels each provided with a corrugated backing and side and corner posts interposed between said panels, bracing elements positioned against the outer sides of each of said walls, and means extending through said posts for tying said elements against said walls.

4. In a concrete wall form construction, spaced outer and inner walls each consisting of a set of sidewise opposed removable wall forming panels each provided with a corrugated backing and side and corner posts interposed between said panels, bracing elements positioned against the outer sides of each of said walls, means extending through said posts for tying said elements against said walls, and spanners detachably mounted in said posts.

5. In a concrete wall form construction,

- spaced outer and inner walls each consisting of a set of sidewise opposed removable wall forming panels each provided with a corrugated backing and side and corner posts 5 interposed between said panels, bracing elements positioned against the outer sides of each of said walls, means extending through said posts for tying said elements against said walls, spanners detachably mounted in said posts, supports for said elements, standards carrying said supports, and combined bracing and anchoring means for the standards.

6. In a concrete wall form construction spaced outer and inner walls, each consisting of a set of sidewise opposed removable wall forming panels and opposed side and opposed corner posts removably interposed between said panels, superposed bracing elements positioned against and extending lengthwise of the outer side of each wall, and means extending through said opposed posts for securing said elements against said walls, said panels, posts, elements and means 10 constructed throughout of metallic material.

7. In a concrete wall form construction spaced outer and inner walls, each consisting of a set of sidewise opposed removable wall forming panels and opposed side and opposed corner posts removably interposed between said panels, superposed bracing elements positioned against and extending lengthwise of the outer side of each wall, means extending through said opposed posts for securing said elements against said walls, said panels, posts, elements and means 15 constructed throughout of metallic material and a metallic backing plate for and arranged against the outer face of each panel.

8. In a concrete wall form construction spaced outer and inner walls, each consisting of a set of sidewise opposed removable wall forming panels and opposed side and opposed corner posts removably interposed between said panels, superposed bracing elements positioned against and extending lengthwise of the outer side of each wall, means extending through said opposed posts for securing said elements against said walls, said panels, posts, elements and means 20 constructed throughout of metallic material, a metallic backing plate for and arranged against the outer face of each panel and corrugated throughout.

9. In a concrete wall form construction spaced outer and inner walls, each consisting of a set of sidewise opposed removable wall forming panels and opposed side and opposed corner posts removably interposed between said panels, superposed bracing elements positioned against and extending lengthwise of the outer side of each wall, means extending through said opposed posts for securing said elements against said walls, said panels, posts, elements and means 25 constructed throughout of metallic material.

10. In a concrete wall form construction spaced outer and inner walls, each consisting of a set of sidewise opposed removable wall forming panels and opposed side and opposed corner posts removably interposed between said panels, superposed bracing elements positioned against and extending lengthwise of the outer side of each wall, means extending through said opposed posts for securing said elements against said walls, said panels, posts, element and means constructed throughout of metallic material, a metallic backing plate for and arranged against the outer face of each panel, metallic supports for said elements, metallic standards carrying said supports, and combined bracing and anchoring means for said standards.

11. In a concrete wall form construction spaced outer and inner walls, each consisting of a set of sidewise opposed removable wall forming panels and opposed side and opposed corner posts removably interposed between said panels, superposed bracing elements positioned against and extending lengthwise of the outer side of each wall, means extending through said opposed posts for securing said elements against said walls, said panels, posts, elements and means constructed throughout of metallic material, and metallic spanner elements removably mounted in said opposed posts.

12. In a concrete wall form construction spaced outer and inner walls, each consisting of a set of sidewise opposed removable wall forming panels and opposed side and opposed corner posts removably interposed between said panels, superposed bracing elements positioned against and extending lengthwise of the outer side of each wall, means extending through said opposed posts for securing said elements against said walls, said panels, posts, elements and means constructed throughout of metallic material, a metallic backing plate for and arranged against the outer face of each panel, and metallic spanner elements removably mounted in said opposed posts.

13. In a concrete wall form construction a wall panel comprising a metallic plate formed with forwardly arranged inwardly extending flanges at the top, bottom and sides thereof thereby providing said plate with inherent means for coupling therewith a backing therefor coextensive therewith, the inturned portions of the flanges at the top and bottom of said plate positioned a greater distance from the outer face of the latter than the distance between the inturned portions of the flanges at the sides of said plate.

14. In a concrete wall form construction a wall panel comprising a metallic plate formed with forwardly arranged inwardly extending flanges at the top, bottom and sides thereof thereby providing said plate with inherent means for coupling therewith a backing therefor coextensive therewith, the inturned portions of the flanges at the top and bottom of said plate positioned a greater distance from the outer face of the latter than the distance between the inturned portions of the flanges at the sides of said plate, said side flanges having the ends thereof separated from the ends of the top and bottom flanges of said plate.
15. In a concrete wall form construction according to claim 13, a vertically corrugated backing plate for said panel, said backing plate having each of its side edges extending in the same plane throughout and its top and bottom edges corrugated, said backing plate positioned between said top and bottom flanges and having its side marginal portions overlapped by said side flanges.
16. In a concrete wall form construction side wise opposed wall forming panels constructed of metal and each formed with forwardly arranged inwardly extending flanges at the top, bottom and sides thereof to provide each panel with inherent coupling means, a

metallic side post interposed between and provided with oppositely disposed means for receiving the opposed sides of a pair of panels, a metallic corner post formed with a pair of lengthwise extending pockets, said corner post arranged between and overlapping the opposed sides of a pair of panels and further having such panels extending into said pockets, and a backing element positioned against the outer face of and coextensive with each panel, each of said backing elements connected at its top, bottom and sides to its associated panel by the inherent coupling means formed on the latter.

17. In a concrete wall form construction according to claim 16, each of said backing elements being vertically corrugated and having a corrugated top and bottom edge and each of the side edges extending in the same plane throughout, the top and bottom flanges of each panel having the inherent portions thereof spaced a greater distance from the outer face than the inturned portions of the side flanges of the panels and whereby the flanges of a panel will snugly overlap the top and bottom edges of a backing element and the side edges thereof.

In testimony whereof, I affix my signature hereto.

OTTO L. ENGSTROM.
